UNITED STATES PATENT OFFICE

118,185

DESIGN FOR A FOLDING CHAIR

Willard H. Bond, Jr., East Grand Rapids, Mich., assignor to American Seating Company, Grand Rapids, Mich., a corporation of New Jersey

Application July 27, 1939, Serial No. 86,267

Term of patent 14 years

To all whom it may concern:

Be it known that I, Willard H. Bond, Jr., a citizen of the United States, residing at East Grand Rapids, in the county of Kent and State of Michigan, have invented a new, original, and ornamental Design for a Folding Chair, of which the following is a specification, reference being had to the accompanying drawing, forming a part thereof, in which:

The characteristic features of my design reside in the grooved chair back best shown in Figure 2.

I claim:

The ornamental design for a folding chair, as shown and described.
